H. A. VANDERBROOK.
FLOOR OR CEILING PLATE.
APPLICATION FILED FEB. 2, 1921.

1,405,465.

Patented Feb. 7, 1922.

H. A. Vanderbrouk INVENTOR.

BY

Arthur L. Schubert ATTORNEY.

UNITED STATES PATENT OFFICE.

HARRY A. VANDERBROUK, OF NEW BRITAIN, CONNECTICUT, ASSIGNOR OF ONE-HALF
TO R. D. HEYMANN, OF HARTFORD, CONNECTICUT.

FLOOR OR CEILING PLATE.

1,405,465.

Specification of Letters Patent. Patented Feb. 7, 1922.

Application filed February 2, 1921. Serial No. 441,805.

To all whom it may concern:

Be it known that HARRY A. VANDERBROUK, a citizen of the United States, residing at New Britain, in the county of Hartford and 5 State of Connecticut, has invented certain new and useful Improvements in Floor or Ceiling Plates, of which the following is a specification.

This invention relates to floor or ceiling 10 plates, among the objects of the invention being the provision of an article which is capable of exceedingly inexpensive construction, which possesses great strength and which comprises but a small number of parts, 15 generally only three.

In the drawing accompanying and forming part of the present specification I have shown in detail one of the several forms of embodiment of the invention which to enable 20 those skilled in the art to practice the same will be set forth fully in the following description. Obviously I am not restricted to this disclosure. I may depart therefrom in several respects within the scope of the invention defined by the claim following said 25 description.

Referring to said drawing:

Figure 1 is a perspective view of a floor or ceiling plate comprising the invention 30 and showing a way of using it.

Fig. 2 is a bottom plan view of the same showing a pipe in cross section and one of the members of the plate as opened by dotted lines.

Figure 3 is a transverse section on the line 3—3 of Fig. 2 showing a way of using the article.

Fig. 4 is a perspective view of the forward portion of the ring, the sections being open. 40 Like characters refer to like parts throughout the several views.

These floor or ceiling plates are usually fitted to steam or water pipes, for finishing purposes. They encircle the pipe adjacent 45 the ceiling or floor and customarily bear against one of the latter. In Fig. 1 I have shown a part of a floor 2 through which the pipe 3 extends. This pipe may be either the supply, or return pipe of a radiator, not 50 shown, or it may be any other desired pipe, the plate shown in said figure being denoted in a general way by 4. Said plate 4 as shown is circular and desirably comprises two semi-circular sections as 5 and 6 which 55 are shown in Fig. 1 as closed about the pipe

3. The full lines in Fig. 2, show the plate as closed around the pipe although the dotted lines in said view show one of the sections as open. Both sections are opened when it is desired to position or remove the plate. 60 Each of the sections 4 has on its outer edge as shown the flange 7. They are provided along their inner edge with a flange 8 both sets of flanges being desirably integral with the respective sections 5 and 6. The inner 65 flanges 8 have at their back ends the lips 9 and 10 which extend laterally of the respective semi-circular sections and which as will be clear are integral with the respective flanges 8. When the plate is closed, the lips 70 or lugs 9 and 10 impinge or abut against each other as shown best by full lines in Fig. 2. The lip 9 is shown as having an arm or projection integral therewith while the lip 10 has integral with it a somewhat similar 75 arm or projection 11 the two arms being practically flat and superimposed. The arms extend rearwardly or outwardly from the respective lips diagonally of the respective sections and are pivoted together in 80 some suitable way the rivet 13 which is generally hollow answering in this particular although some other form of pivot may be provided. This permits the sections of the plate to be relatively opened and closed. I 85 should remark at this time that the sections of the plate are desirably made from sheet metal so as to secure a certain and a requisite amount of resiliency at proper points.

The forward end of the flange 8 has at 90 its forward end the L-shaped projection 14 constituting a suitable latching member, the latching or operative portion being denoted by 15 and extending beyond the forward or free end of said section 5 as clearly shown 95 in Fig. 4. The flange 8 of the section 6 is shown as having at its forward end and integral therewith the keeper 16 shown as a lateral flange and the upper edge portion of which has a notch 17.

It will be assumed that the plate is open as shown by Fig. 4. As the sections 5 and 6 approach the free end of the latch 15 engages the keeper or flange 16 at the notch 17 therein so that the cam surface of the 105 latch 18 which is integral with its flange 8 will engage and ride over the lower wall of the notch or slot 17, the section 5 being tipped upward during this action when the latching or operative portion 15 passes beyond 110

the keeper flange 16 the latching portion 15 will be snapped back of the keeper flange 16 to maintain the ring closed. It can be opened by reversing the described action.

5 The flanges 8 about centrally thereof are cut away or concaved as at 19 and the butts of the forked springs 20 are integrally connected with the low portions of the recesses 19. These springs 20 are integral with the 10 respective sections 5 and 6 being formed in one piece with the respective flanges thereof. They can be bent or flexed for adjustability at their points of union with the respective flanges so as to vary the span of 15 the forked spring as shown by full and dotted lines in Fig. 3. The free ends of the branches of the forked springs are somewhat enlarged as shown at 21, these enlarged portions engaging the surfaces of a pipe so that 20 when two springs are present which is the desirable but not essential relation, the pipe will be engaged at four places. It will be evident that the shanks of the two Y formed

springs are rigid with the respective sections of the plate, and the shanks are practically 25 perpendicular to the planes of the sections.

What I claim is:

A floor or ceiling plate comprising a plurality of semi-annular sections pivotally connected together and opposed springs of Y 30 form, the butts of the shanks of the springs being rigid with the respective sections and the shanks extending approximately perpendicularly from the sections, the heads or free ends of the springs being free and being 35 of a compound-curvature, the central portions of the heads being concaved and the ends being convex to bear against the surface of a part surrounded by the plate, the latter having means for preventing the said sections being accidentally opened.

In testimony whereof I affix my signature.

HARRY A. VANDERBROUK.
